UNITED STATES PATENT OFFICE.

ROBERT WILLIAM VAIL, OF NEW YORK, N. Y.

SAFETY-ENVELOP.

No. 877,532.

Specification of Letters Patent.

Patented Jan. 28, 1908.

Application filed June 14, 1906. Serial No. 321,781.

To all whom it may concern:

Be it known that I, ROBERT WILLIAM VAIL, a citizen of the United States, and resident of New York, in the county and State of 5 New York, have invented certain new and useful Improvements in Safety-Envelops, of which the following is a specification.

This invention relates to safety envelops, and it has for its object to provide a simple 10 and improved envelop of this class which will effectively prevent unsealing and tampering with the contents without detection.

A further object of my invention is to provide an improved envelop of the class described which will possess advantages in 15 point of security, safety, convenience, inexpensiveness, effectiveness, and general efficiency.

In carrying out the objects above stated, 20 my invention comprises an improved envelop in which safety sealing by means of a mass of sealing-wax or plastic material is enabled, which sealing means is adapted, by the structural features of the envelop, to so 25 engage the paper of which the envelop is constructed that any breakage or destruction of said sealing means and an attempt to restore the same to original condition will be readily detected.

30 In the drawings—Figure 1 is a rear face view of the envelop when sealed. Fig. 2 is a rear face view of the envelop with the sealing-flap in elevated position. Fig. 3 is a detail front face view of the sealing structure comprised in the back-sheet. Fig. 4 is a detail 35 rear face view of the sealing structure comprised in the sealing-flap. Fig. 5 is a detail sectional view, taken on the line $x-x$, Fig. 1. Fig. 6 is a detail cross-section of one of the 40 projecting tongues, taken on the line $z-z$, Fig. 3. Fig. 7 is a detail face view corresponding to Figs. 3 and 4 and illustrating a modified construction. Fig. 8 is a detail 45 sectional view, taken on the line $y-y$, Fig. 7. Fig. 9 is a detail sectional view corresponding to a portion of Fig. 5 and illustrating a supplementary construction.

Corresponding parts in all the figures are denoted by the same reference characters.

50 Referring to the drawings, 1 designates the body of the envelop, which is in the main of ordinary or usual construction, comprising the back-sheet, 2, and the sealing-flap, 3, which latter may carry the usual sealing ma-

terial, such as mucilage or the like, at its edge, 55 as at 4.

At a convenient point on the portion of the back-sheet 2 which is covered by the sealing-flap 3, the back-sheet is provided with an outwardly-projecting ridge, as at 5, preferably 60 of annular or circular contour and having corrugations, as at 6, for the purpose of strengthening or facilitating the retention of the normal contour of said ridge, this normal contour being preferably convex, as shown. 65 The paper of the back-sheet 2 is cut away, within the ridge 5, to form open portions or spaces, as at 7, thus forming intervening projecting paper-portions within the ridge 5, which projecting portions may be in the 70 form of tongues, as shown at 8 in Figs. 2 and 3. The sealing-flap 3 is likewise provided with a corresponding ridge, as at 9, at a suitable point adapted to register with the ridge 5 of the back-sheet 2, when the flap is sealed, 75 and overlap or fit over said ridge 5, said ridge 9 of the sealing-flap 3 therefore projecting outwardly in a convex manner corresponding to the ridge 5 of the back-sheet 2. In general construction and arrangement the 80 ridge and associate structure of the sealing-flap 3 corresponds to the corresponding registering structure of the back-sheet 2, the ridge 9 preferably having similar corrugations, as at 10, and the sealing-flap having 85 similar open or cut away portions within its ridge, as at 11, forming similar projecting tongues, as at 12. The relative construction is preferably such that the tongues 8 and 12 of the respective back-sheet and sealing-flap 90 portions project at opposite points and when the parts are registered have an intermediate position with respect to each other, whereby the combined series of tongues are in circular or concentric arrangement within the registering ridges when the flap 3 is in secured position or sealed by its adhesive edge 4 to the back-sheet 2.

The edges of the tongues 8 and 12 are preferably turned outwardly, as at 14, in a corresponding relative manner and direction with respect to the succession of the tongues forming the complete circular series when the ridges 5 and 9 register, for which purpose the tongues preferably have a portion of the 100 edges which are thus turned notched or cut away, as at 15, at the point of junction of the tongue with the ridge which is comprised in

the paper sheet forming respectively the back-sheet 2 and the sealing-flap 3. The tongues 8 and 12 may be strengthened or stiffened in the maintenance of their projecting position and turned edges by corrugations extending through the tongues and from the ridges, as shown at 16, which formation will impart to the projecting tongues an outwardly-bowed or convex contour.

10 The ridges and tongues, with their corrugations or indentations and turned edges and other structural characteristics as hereinabove described, may be formed by a suitable embossing or pressing machine acting 15 upon the back-sheet 2 and sealing-flap 3, and at the same time or in the same machine the open or cut-away portions, 7 and 11, respectively, may be formed.

When the flap 3 is sealed or brought to relative position with respect to the back-sheet 2, and the ridge 9 overlaps and registers with the ridge 5, there is formed at the outside of the sealing-flap a cup-shaped depression, as at 17, for containing sealing wax or other 25 suitable plastic material, shown at 18. In applying the wax 18, it may be turned in the direction indicated by the arrow in Fig. 3, so that it will engage under the turned edges 14 of the projecting tongues and fill the space 30 between and under all of the tongues and within the outside depression or cup 17. After the wax is applied, in the manner just stated, it can be impressed at its outer surface with a desired initial, emblem or mark, 35 as at 19, forming an identifying seal.

To prevent the wax 18 from contacting with or affecting or injuring the contents of the envelop, when the safety sealing is effected by the application of the wax as above 40 described, and to furthermore augment the safety efficiency of the improved envelop, the back-sheet 2 may be interiorly provided with a strip or flap, 20, secured adhesively or otherwise, as at 21, to the inner surface of the 45 back-sheet, and underlying or extending across and beneath the open or cut-away portions 7 which are within the ridge 5 of the back-sheet. The wax 18, in filling the space 50 between the registering ridges 5 and 9 and around the tongues 8 and 12, is thus retained by the strip 20 from contact with the contents of the envelop, and said protective strip 20 is preferably formed of an absorbent 55 paper or analogous material which will by absorption mingle with the wax and form a secure or permanent contact or connection therewith. It will be noted that the wax 18 covers and incloses within its mass or body all of the projecting paper-tongues 8 and 12, 60 or the paper structure extending in the space within the registering and overlapping ridges 5 and 9, and adheres thereto, as well as to the interior protective covering or strip 20.

The operation and advantages of my in-

vention will be readily understood. When 65 the flap 3 is brought to operative position with relation to the back-sheet 2, or sealed thereto by its adhesive edge 4, and the wax 18 is applied within the space between the registering ridges 5 and 9 with its mass inclosing the projecting portions 8 and 12 within said ridges and passing through the open or cut away portions 7 and 11 and contacting with the interior strip 20, and the outer surface of the wax is sealed with the identifying 70 mark 19, the envelop is effectively sealed against unsealing or tampering with the contents without detection. The release of the sealing edge 4 by steaming or otherwise, would of course leave the wax seal-construction 75 intact, and the destruction of the wax seal 18 would not only destroy the identifying mark 19 but would also essentially destroy the projecting paper-portions or tongues 8 and 12 which are within the mass of the 80 wax, and would also destroy the adhering interior protective strip or flap 20 and the contour of the ridges 5 and 9, and thus any attempt to provide a substitute wax seal could be detected. The invention thus provides 85 an effective sealing medium against any tampering with the contents of the envelop without detection, in which connection it will be especially noted that the means by 90 which the wax seal 18 is adhesively connected to the paper of the envelop, and also the surrounding parts, are essentially destroyed 95 if the wax seal is broken or removed, inasmuch as such adhesive connections are embedded and inclosed within and surrounded 100 by a mass or body of the wax.

Under some circumstances of use, it will be understood that the employment of the sealing edge 4 is not essential, as the improved structure associated with the wax seal 105 18, as comprised in my invention and improvements and herein described, will effectively serve all sealing purposes in the use and transportation of the envelop. It will be further noted that the improved structure, 110 comprising the projecting ridges surrounding the wax seal, forms an effective protection for the wax seal against damage or breakage thereto, and leaves no projecting edges of the wax upon a free or exposed surface of the paper, which would be liable to be engaged and result in accidental breakage of 115 or damage to the wax seal, as is the case when wax seals are applied in the usual manner to free or exposed surfaces of paper.

The projecting portions of the paper which are inclosed within the mass or body of the wax seal 18 and which exist in the space within the ridges 5 and 9 intermediately between the open or cut-away portions 7 and 125 11, need not essentially be in the form of the projecting tongues or strips 8 and 12, but may be of any other suitable or adapted form

or arrangement which will provide projecting paper-portions or strips equivalent to said tongues and intervening open or cut-away portions. For instance, the paper 5 within the ridges may be simply perforated or provided with any suitably-shaped openings or slots. In this connection, I have shown one form of modification in Figs. 7 and 8, in which the portion of the paper with- 10 in the ridges is irregularly cut out or perforated, to form a lace-work consisting of connected ribs or cross-pieces, as at 22, separated by intervening open or cut-away portions, as at 23. In such modification, or 15 other analogous modifications, where the portion of the paper within the ridges is perforated or slotted, said portion is preferably pressed or stamped into convex contour, as shown in Fig. 8, so that the wax 18 may 20 spread under and around all of said portions which are to be embedded in its mass or body.

In Fig. 9, I have illustrated a supplementary construction, embodying a stiffening 25 plate or strip, as at 24, which is preferably of annular or ring form and may be constructed of a thin piece of aluminium or any other adapted material. This plate is secured in position by the protective strip or flap 20 and 30 embodies a ridge or projection, as at 25, entering the ridge 5 of the back-sheet 2 and preferably conforming thereto, whereby both the ridges 5 and 9 will be strengthened and maintained in their normal contour. The 35 inner edge of the plate 24 may be bent up to form projections, as at 26, preferably of angular form, which will project through the open portions 7 and 11, at the edge of said open portions, and thus serve not only to brace 40 and maintain the adjacent structural parts of the back-sheet 2 and sealing-flap 3 in normal contour but will also be engaged and surrounded by the mass of wax 18 and thus constitute an additional means for effectively se- 45 curing the wax and preventing undetected tampering therewith.

I do not desire to be understood as limiting myself to the detail construction and arrangement of parts as herein shown and de- 50 scribed, as it is manifest that variations and modifications therein may be resorted to, in the adaptation of my invention to varying conditions of use, without departing from the spirit and scope of my invention and improve- 55 ments. I therefore reserve the right to all such variations and modifications as properly fall within the scope of my invention and the terms of the following claims.

Having thus described my invention, I 60 claim and desire to secure by Letters Patent:

1. An improved safety envelop of the class described, having the paper or material constituting its meeting portions formed into corresponding outwardly - projecting ridges

integral with the body of said meeting por- 65 tions and arranged to relatively register and overlap one upon the other when the envelop is closed, said overlying outwardly-projecting integral ridge of the paper or material constituting the meeting portion of the en- 70 envelop being adapted to be engaged by the mass of a plastic sealing material.

2. An improved safety envelop of the class described, having the paper or material constituting its meeting portions formed into 75 corresponding outwardly - projecting ridges provided with corrugations or ribs to strengthen and retain the contour, the ridges being integral with the body of said meeting portions and arranged to relatively register 80 and overlap one upon the other when the envelop is closed, said overlying outwardly-projecting integral ridge of the paper or material constituting the meeting portion of the envelop being adapted to be engaged by 85 the mass of a plastic sealing material.

3. An improved safety envelop of the class described, having the paper or material constituting its meeting portions formed into corresponding outwardly - projecting ridges 90 which are convex in cross-section and integral with the body of said meeting portions and arranged to relatively register and overlap one upon the other when the envelop is closed, said overlying outwardly-projecting 95 integral ridge of the paper or material constituting the meeting portion of the envelop being adapted to be engaged by the mass of a plastic sealing material.

4. An improved safety envelop of the class 100 described, having the paper or material constituting its meeting portions formed into corresponding outwardly - projecting ridges which are convex in cross-section and provided with corrugations or ribs to strengthen 105 and retain the contour, the ridges being integral with the body of said meeting portions and arranged to relatively register and overlap one upon the other when the envelop is closed, said overlying outwardly-projecting 110 integral ridge of the paper or material constituting the meeting portion of the envelop being adapted to be engaged by the mass of a plastic sealing material.

5. An improved safety envelop of the class 115 described, having the paper or material constituting its meeting portions formed into corresponding outwardly - projecting ridges constituting an exterior cup for retaining the mass of a plastic sealing material and integral with the body of said meeting portions and arranged to relatively register and overlap one upon the other when the envelop is closed.

6. An improved safety envelop of the class 125 described, having the paper or material constituting its meeting portions formed into corresponding outwardly - projecting ridges

integral with the body of said meeting portions and arranged to relatively register and overlap one upon the other when the envelop is closed, the portion of the paper or material 5 constituting the meeting portions of the envelop being cut away in the space within said ridges to form openings adapted to receive the mass of a plastic sealing material placed in the space within said ridges.

10 7. An improved safety envelop of the class described, having the paper or material constituting its meeting portions formed into corresponding outwardly-projecting ridges integral with the body of said meeting portions and arranged to relatively register and overlap one upon the other when the envelop is closed, the portion of the paper or material constituting the meeting portions of the envelop being formed into tongues or strips 15 projecting into the space within said ridges and adapted to be engaged by the mass of a plastic sealing material placed in the space within said ridges.

20 8. An improved safety envelop of the class described, having the paper or material constituting its meeting portions formed into corresponding outwardly-projecting ridges integral with the body of said meeting portions and arranged to relatively register and overlap one upon the other when the envelop is closed, the portion of the paper or material constituting the meeting portions of the envelop being formed into tongues or strips 25 having outwardly-turned edges and projecting into the space within said ridges and adapted to be engaged by the mass of a plastic sealing material placed in the space within said ridges.

30 9. An improved safety envelop of the class described, having the paper or material constituting its meeting portions formed into corresponding outwardly-projecting ridges integral with the body of said meeting portions and arranged to relatively register and overlap one upon the other when the envelop is closed, the portion of the paper or material constituting the meeting portions of the envelop being formed into tongues or strips 35 having edges turned outwardly in a corresponding relative manner with respect to the succession of tongues or strips forming the complete series when the ridges meet and register.

40 10. An improved safety envelop of the class described, having the paper or material constituting its meeting portions formed into corresponding outwardly-projecting ridges 45 integral with the body of said meeting portions and arranged to relatively register and overlap one upon the other when the envelop is closed, the portion of the paper or material

constituting the meeting portions of the envelop being formed into tongues or strips projecting into the space within said ridges and adapted to be engaged by the mass of a plastic sealing material placed in the space within said ridges, said tongues or strips 50 upon the respective meeting portions of the envelop projecting in non-registering position when the envelop is closed.

11. An improved safety envelop of the class described, having the paper or material constituting its meeting portions formed into corresponding outwardly-projecting ridges integral with the body of said meeting portions and arranged to relatively register and overlap one upon the other when the envelop 55 is closed, the portion of the paper or material constituting the meeting portions of the envelop being formed into tongues or strips projecting into the space within said ridges and adapted to be engaged by the mass of a 60 plastic sealing material placed in the space within said ridges, said tongues or strips upon the respective meeting portions of the envelop projecting in non-registering position when the envelop is closed and having outwardly-turned edges.

12. An improved safety envelop of the class described, having the paper or material constituting its meeting portions formed into corresponding outwardly-projecting ridges 65 integral with the body of said meeting portions and arranged to relatively register and overlap one upon the other when the envelop is closed, the portion of the paper or material constituting the meeting portions of the envelop being formed into tongues or strips projecting into the space within said ridges and adapted to be engaged by the mass of a 70 plastic sealing material placed in the space within said ridges, said tongues or strips upon the respective meeting portions of the envelop projecting in non-registering position when the envelop is closed and having outwardly-turned edges.

13. An improved safety envelop of the class described, having the paper or material constituting its meeting portions formed into corresponding outwardly-projecting ridges 75 integral with the body of said meeting portions and arranged to relatively register and overlap one upon the other when the envelop is closed, the portion of the paper or material constituting the meeting portions of the envelop being formed into tongues or strips 80 projecting into the space within said ridges and adapted to be engaged by the mass of a 85 plastic sealing material placed in the space within said ridges, said tongues or strips upon the respective meeting portions of the envelop projecting in non-registering position when the envelop is closed and having outwardly-turned edges.

14. An improved safety envelop of the class described, having the paper or material

14. An improved safety envelop of the class described, having the paper or material constituting its meeting portions formed into projecting tongues or strips provided with 65 outwardly-turned edges and adapted to be engaged by the mass of a plastic sealing material passing under said outwardly-turned edges.
15. An improved safety envelop of the 10 class described, having the paper or material constituting its meeting portions formed into projecting tongues or strips with edges turned outwardly in a corresponding relative manner with respect to the succession of 15 tongues or strips forming the complete series when the meeting portions of the envelop register, said tongues or strips being adapted to be engaged by the mass of a plastic sealing material passing under said outwardly-turned 20 edges.
16. An improved safety envelop of the class described, having the paper or material constituting its meeting portions formed into projecting tongues or strips adapted to be 25 engaged by the mass of a plastic sealing material, said tongues or strips upon the respective meeting portions of the envelop projecting in non-registering position when the envelop is closed.
17. An improved safety envelop of the 30 class described, having the paper or material constituting its meeting portions formed into projecting tongues or strips adapted to be engaged by the mass of a plastic sealing material, said tongues or strips upon the respective meeting portions of the envelop projecting in non-registering position when the envelop is closed and having outwardly-turned 35 edges.
18. An improved safety envelop of the 40 class described, having the paper or material constituting its meeting portions formed into projecting tongues or strips adapted to be engaged by the mass of a plastic sealing material, said tongues or strips upon the respective meeting portions of the envelop projecting in non-registering position when the envelop is closed and having edges turned outwardly in a corresponding relative manner 45 with respect to the succession of tongues or strips forming the complete series when the meeting portions of the envelop register.
19. An improved safety envelop of the 50 class described, having the paper or material constituting its meeting portions formed into corresponding outwardly-projecting ridges integral with the body of said meeting portions and arranged to relatively register and overlap one upon the other when the envelop 55 is closed, the portion of the paper or material constituting the meeting portions of the envelop being cut away in the space within said ridges to form openings adapted to receive the mass of a plastic sealing material placed 60 in the space within said ridges, and the underlying meeting portion being provided with a separate protective strip extending across and beneath said 65 openings and adapted to be absorbently engaged by the mass of a plastic sealing material.
20. An improved safety envelop of the class described, having the paper or material 70 constituting its meeting portions formed into corresponding outwardly-projecting ridges integral with the body of said meeting portions and arranged to relatively register and overlap one upon the other when the envelop 75 is closed, the portion of the paper or material constituting the meeting portions of the envelop being cut away in the space within said ridges to form openings adapted to receive the mass of a plastic sealing material placed 80 in the space within said ridges, and the underlying meeting portion being provided with a separate protective strip of absorbent material extending across and beneath said 85 openings and adapted to be absorbently engaged by said plastic sealing material.
21. An improved safety envelop of the class described, having the paper or material constituting its meeting portions formed into corresponding outwardly-projecting ridges 90 integral with the body of said meeting portions and arranged to relatively register and overlap one upon the other when the envelop is closed, the portion of the paper or material constituting the meeting portions of the envelop being formed into tongues or strips projecting into the space within said ridges and adapted to be engaged by the mass of a plastic sealing material placed in the space within 95 said ridges, and the underlying meeting portion being provided with a separate protective strip extending across and beneath said 100 tongues or strips.
22. An improved safety envelop of the class described, having the paper or material 105 constituting its meeting portions formed into corresponding outwardly-projecting ridges integral with the body of said meeting portions and arranged to relatively register and overlap one upon the other when the envelop 110 is closed, the portion of the paper or material constituting the meeting portions of the envelop being formed into tongues or strips projecting into the space within said ridges and adapted to be engaged by the mass of a plastic sealing material placed in the space within 115 said ridges, and the underlying meeting portion being provided with a separate protective strip of absorbent material extending across and beneath said tongues or strips and adapted to be absorbently engaged by 120 said plastic sealing material.
23. An improved safety envelop of the class described, having the paper or material constituting its meeting portions cut away 125 to form registering openings and integral tongues or strips projecting into said openings and adapted to be engaged by the mass

- of a plastic sealing material, the underlying meeting portion being provided with a separate protective strip extending beneath and across said openings and tongues and adapted 5 to be engaged by said plastic sealing material.
24. An improved safety envelop of the class described, having the paper or material constituting its meeting portions cut away to form registering openings and integral 10 tongues or strips projecting into said openings and adapted to be engaged by the mass of a plastic sealing material, the underlying meeting portion being provided with a separate protective strip of absorbent material 15 extending beneath and across said openings and tongues and adapted to be absorbently engaged by said plastic sealing material.
25. An improved safety envelop of the 20 class described, having the paper or material constituting its meeting portions formed into corresponding outwardly - projecting ridges constituting an exterior cup for retaining the mass of a plastic sealing material 25 and integral with the body of said meeting portions and arranged to relatively register and overlap one upon the other when the envelop is closed, the portion of the paper or material constituting the meeting portions 30 of the envelop being cut away in the space within said ridges constituting the exterior cup to form openings adapted to receive the mass of a plastic sealing material, and the underlying meeting portion being provided 35 with a separate protective strip extending beneath and across said openings and forming the bottom of the cup.
26. An improved safety envelop of the 40 class described, having the paper or material constituting its meeting portions formed into corresponding outwardly - projecting ridges constituting an exterior cup for retaining the mass of a plastic sealing material and integral with the body of said meeting 45 portions and arranged to relatively register and overlap one upon the other when the envelop is closed, the portion of the paper or material constituting the meeting portions of the envelop being cut away in the space 50 within said ridges constituting the exterior cup to form openings adapted to receive the mass of a plastic sealing material, and the underlying meeting portion being provided 55 with a separate protective strip of absorbent material extending beneath and across said openings and constituting an absorbent bottom for the cup.
27. An improved safety envelop of the 60 class described, having the paper or material of the envelop formed into an outwardly-projecting integral ridge constituting an exterior cup for retaining the mass of a plastic sealing material and having openings coincident with the space or area inclosed by
- 65 said cup, and provided with separate protective strip underlying said openings and forming the cup bottom.
28. An improved safety envelop of the class described, having the paper or material constituting its meeting portions formed into corresponding outwardly - projecting ridges integral with the body of said meeting portions and arranged to relatively register and overlap one upon the other when the envelop is closed, said overlying outwardly-projecting integral ridge of the paper or material constituting the meeting portion of the envelop being adapted to be engaged by the mass of a plastic sealing material, and provided with a stiffening plate interiorly projecting within said registering integral ridges. 70
- 75
29. An improved safety envelop of the class described, having the paper or material constituting its meeting portions formed into corresponding outwardly - projecting ridges integral with the body of said meeting portions and arranged to relatively register and overlap one upon the other when the envelop is closed, the portion of the paper or material constituting the meeting portions of the 80 envelop being cut away in the space within said ridges to form openings adapted to receive the mass of a plastic sealing material placed in the space within said ridges, and provided with a stiffening plate interiorly 85 projecting within said registering integral ridges, the underlying meeting portion having a securing strip retaining said stiffening plate in connection therewith and extending beneath and across said openings. 90
- 95
30. An improved safety envelop of the class described, having the paper or material constituting its meeting portions formed into corresponding outwardly - projecting ridges integral with the body of said meeting portions and arranged to relatively register and overlap one upon the other when the envelop is closed, the portion of the paper or material constituting the meeting portions of the 100 envelop being cut away in the space within said ridges to form openings adapted to receive the mass of a plastic sealing material placed in the space within said ridges, and provided with a stiffening plate interiorly 105 projecting within said registering integral ridges, the underlying meeting portion having a securing strip of absorbent material retaining said stiffening plate in connection therewith and extending beneath and across 110 said openings and adapted to be absorbently 115 engaged by said plastic sealing material. 120
31. An improved safety envelop of the class described, having the paper or material constituting its meeting portions formed into corresponding outwardly-projecting ridges integral with the body of said meeting portions and arranged to relatively register and overlap one upon the other when the envelop 125

is closed, the portion of the paper or material constituting the meeting portions of the envelop being cut away in the space within said ridges to form openings adapted to receive the mass of a plastic sealing material placed in the space within said ridges, and a stiffening plate interiorly projecting within the registering integral ridges and having projections extending within said openings.

In testimony whereof I have signed my name in the presence of the subscribing witnesses.

ROBERT WILLIAM VAIL.
